HINGE STRUCTURE

Charles H. Lindley, St. Louis, and Oscar Sliger,
University City, Mo.

Application January 13, 1939, Serial No. 250,725

4 Claims. (Cl. 16—150)

This invention pertains to flexible hinges especially applicable to lids of boxes, crates and containers that are returned to the shipper and repeatedly used such as is in extensive use by 5 distributors of bottled beverages.

Utilizing a flexible device such as fabric or a plurality of united strands of fibre as by weaving or molding for attaching a lid to a box constitutes an essential object of our invention.

10 Hinges of this type possess obvious merit for attaching lids especially to light weight boxes of the type disclosed in the application for United States Letters Patent entitled Box and the method of making same, filed January 13, 1939, 15 Ser. No. 250,724, by Charles H. Lindley and Oscar Sliger.

An object of this invention is to employ a flexible tape as a hinge and to utilizing it for swingably attaching a very thin lid to a box 20 without the use of other means for securing the hinge to the lid.

A further object is to attach a lid to a box by passing a flexible member through and over the adjacent margins of the lid and a side of box, 25 then securing the ends of the tape.

Providing a hinge for attaching a lid without employing conventional screws, nails or rivets, or the labor incident to their use is a feature of this invention.

30 Other features and objects of our invention will be apparent in the following detailed description made in connection with the annexed drawing, and from the appended claims, which distinctly point out and define the scope of this 35 invention.

In the annexed drawing:

Figure 1 is a perspective view of a box having a lid attached thereto by a pair of hinges made in accordance with this invention.

40 Figure 2 is an elevation of a section of a back side of the box and a corresponding section of a lid in open relation thereto substantially as shown in Figure 1, the lid being attached to the box by the hinge member.

45 Figure 3 is a vertical section of Figure 2 along the line 3—3.

Numerals 5, 6 and 7 indicate respectively, an end, back side and the lid of the box.

In carrying out this invention, hole 61, recess 50 62 and notch 63 are made in side member 6, also a corresponding hole 71, recess 72 and notch 73 are made in side member 7, prior to the assembling of the box. The notches and recesses are made of sufficient depth and width to receive 55 and dispose hinge 8 so that it will be protected

from abrasion when the box is put into service, at which time it is exposed to contact with other objects. It will be noted by this arrangement that the lid will orient on the fabric without being pinched, all of which is in the interest 5 of long life for the hinge.

In practice it has been found sufficient for ordinary usages to limit the recessing to the outside of the box, however, it is to be understood that these recesses could likewise be placed on 10 the inside in the event certain conditions develop wherein this would contribute to the length of service to be procured from the hinge. By the arrangement shown in the drawing, a hinge of 15 long endurance is procured without the use of metal parts, which, although possessing greater strength for like dimensions are objectionable in that they are expensive to produce and mount and should be made either of a non-ferrous 20 metal or if ferrous metals are used they require surface coating where long life and/or appearance are factors.

The lid is attached to the box by a plurality of fabric strips indicated by numeral 8. With reference to Figure 3, in the embodiment of this 25 invention selected for the purpose of illustration, end 81 of fabric strip 8 is placed on the inside of the box and manually held or permanently secured, while the other end 82 is threaded through hole 61 past notches 63, 73, then through 30 hole 71, then through said notches at substantially 90 degrees to the located position of fabric strip, and then stretched and disposed over the first mentioned end so as to lap end 81 where it is secured. Staple 9 is used for finally attaching 35 the hinge; it preferably projects through both ends 81, 82 and through side 6 where it is clinched on the outside as indicated by numeral 91 in Figure 3. Rivets, screws or an adhesive can be substituted for the staple to advantage 40 under certain conditions, the requirement being that the fabric hinge be drawn sufficiently tight and secured so as to result in an operative hinge for attaching the lid to the box.

It will be noted by this structure that the 45 objects of the invention as set forth at the outset of the specification are obviously obtained.

Having thus described our invention, we claim:

1. A strip of flexible material attached to a lid and a box for swingably mounting the lid on 50 the box, said lid member and a side member of the box each having a hole in proximity to juxtaposed edges thereof, said members also having a notch cut in the edges thereof and in alignment with said holes, said strip being threaded 55

- through said holes and crossed in said notches, and the ends of said strip being secured.
2. A strip of flexible material attached to a lid and a box for swingably mounting the lid on the box, said lid member and a side member of the box each having a hole in proximity to juxtapositioned edges thereof, each of said members also having a notch cut in the edges thereof and in alignment with said holes, and a recess external of the box and communicating with said holes, said strip being threaded through said holes and disposed in said recesses and crossed in said notches, and the ends of said strip being secured.
15. 3. A strip of flexible material attached to a lid and a box for swingably mounting the lid on the box, said lid and a side member of the box each having a hole in proximity to juxtapositioned edges thereof, said lid and member each having a

notch cut in the edges thereof, said strip being threaded through said holes and crossed in said notches with the edges of said strip abutting therein, and the ends of said strip being secured.

4. A strip of flexible material attached to a lid and a box for swingably mounting the lid on the box, said lid member and a side member of the box each having a hole in proximity to juxtapositioned edges thereof, each of said members also having a notch cut in the edge and in alignment with said holes, and an external recess extending from the hole to the notch in each member, said strip being threaded through said holes and disposed in said recesses and crossed in said notches, and the ends of said strip being secured, said strip being disposed within the outside surfaces of the box.

CHARLES H. LINDLEY.
